UNITED STATES PATENT OFFICE

LOW MCKINNEY, OF ERIE, PENNSYLVANIA, ASSIGNOR TO THE GRISWOLD MANUFACTURING COMPANY, OF ERIE, PENNSYLVANIA, A CORPORATION OF PENNSYLVANIA

ELECTRIC HEATER

Application filed May 9, 1928. Serial No. 276,438.

This invention is designed to improve electric heaters. This is accomplished by improving the method of supporting a heating element. Features and details of the invention will appear from the specification and claims.

A preferred embodiment of the heater and method is illustrated in the accompanying drawing as follows:—

10 Fig. 1 shows a central section of an electric heater, this being in the specific form shown a waffle iron.

Fig. 2 a bottom view of the hot plate.

15 Fig. 3 an enlarged perspective view of one of the element supports.

Fig. 4 a mold showing the manner of securing the supports to the hot plate.

20 1 marks the heater frame, 2 a closure plate formed on the frame, and 3 a hot plate mounted on the frame above the closure plate.

25 A series of insulating electric element supports 4 are mounted on the plate 3. These supports have openings 5 through them and are, as shown, arranged circumferentially around the plate and the heating element 6 is threaded through the openings 5, the ends being secured in the terminals 7.

30 Each support is provided with sockets 8 extending from one surface of the support and these sockets have vent openings 9 extending through the opposite face of the support.

35 In securing the supports to the plate the following method is employed: 10 represents the drag of an ordinary mold flask and 11 the cope. A mold cavity 12 is formed in the sand of the drag of the mold and cope, this mold cavity being suitable to receive the metal forming the hot plate. At the same time the 40 pattern has prints corresponding in shape to the supports 4 and form the print cavities 13 extending from the mold cavity. The supports 4 are placed in these print cavities in the mold and the metal is then poured filling 45 the mold as shown in Fig. 4. As the metal is poured it flows into the sockets 8 and the cooling of the metal thus secures the supports to the plate. The sockets extending in a perpendicular direction to the plate facilitate 50 this although this is not essential for all

forms of supports. The metal flowing into these cavities, or sockets, makes a nice fit with the sockets without exerting undue strain on any localized point. Consequently the insulating supports which are ordinarily porcelain and fragile will stand a great deal more pressure, or shock, than with ordinary means of securing such supports where such strains are from necessity localized on points of contact. The engaging surfaces conform exactly to the surfaces of the supports even though there may be quite a variation and thus there is an intimate contact between the supports and the plate through which there may be heat transfer from the element to the plate and this intimate relation is also true with relation to heat transfer by way of the securing plugs, or projections 14. The apparatus, therefore, is stronger than the ordinary means of support, the forming of the mold 55 cavities takes no longer than it would without the prints for the insulating supports and the placing of the insulating supports requires less time than any ordinary operation that would secure them to the plate and there is an absence of localized contact with the insulating material so that there is less liability of breakage and greater heat transfer than with the common methods of securing such devices. 60

65 What I claim as new is:—

1. In an electric heater, the combination of an electric heating element; insulating supports for the element; a plate heated by the element, said element being exposed between the supports and in radiating relation to the plate; and means securing the support to the plate, the engaging surface of the plate with the support being a cast of the opposing engaging surface of the support whereby 70 there is a continuous heat exchanging contact between the support and plate. 75

2. In an electric heater, the combination of an electric heating element; insulating supports for the element, said support having 80 sockets; and a plate having projections extending integrally from the plate into said sockets securing the support to the plate, the engaging surface of the plate and projection being a cast of the opposing surfaces on 85 90 95 100

the supports, said element being exposed between said supports and in radiating relation to said plate.

3. In an electric heater, the combination of an electric heating element; insulating supports for said element, said support having sockets; and a plate of metal having integral projections extending into the sockets, the walls of the sockets extending around and engaging the walls of the projections to secure the support to the plate, the heating element being exposed between its supports and in radiating relation to the plate.

4. In an electric heater, the combination of electric heating element; insulating supports for said element, each of said supports having an element receiving opening for the heating element and a securing socket; and a plate of metal having integral projections extending into the sockets of the supports, the walls of the sockets extending around and engaging the projections for securing the supports on the plates, said element being exposed between its supports and in radiating relation to the plate.

25 In testimony whereof I have hereunto set my hand.

LON McKINNEY.
